BACKGROUND OF THE INVENTION

The invention relates generally to gas operating system components for semi-automatic and automatic firearms. Many people own firearms for various purposes including, but not limited to, protection, trade, hunting, recreation, collecting, and sporting.

Semi-automatic and automatic firearms offer a number of benefits over manually operated firearms. Semi-automatic and automatic firearms generally permit an operator to fire rounds more rapidly than do manually operated firearms. Semi-automatic firearms also generally impart a less harsh recoil impulse to an operator.

A variety of operating systems are employed by semi-automatic and automatic firearms including, but not limited to, blow-back, piston, and direct impingement. A blow-back operating system is generally used on lower pressure cartridges. Piston and direct-impingement operating systems are generally used on higher pressure cartridges. Piston and direct-impingement operating systems are generally used on locking bolt firearms. Piston and direct-impingement operating systems generally rely on a hole, called a gas port, between the chamber and the muzzle of the barrel. When the firearm is fired, a primer ignites powder in the cartridge generating gas. The expanding gas causes pressure to increase forcing the bullet to leave the cartridge and travel down the barrel. Once the bullet passes the port, some of the gas flows out the gas port activating the operating system.

Many direct-impingement operating systems are not user-adjustable. These operating systems rely on allowing sufficient gas to enter the operating system to allow cartridges within a particular band of pressures to successfully activate the operating system. This results in the operating system commonly having excessive operating force under certain

2

conditions causing greater than necessary perceived recoil and equipment wear. This can also result in the operating system having insufficient operating force and not reliably functioning in certain other conditions.

5 An optimally adjusted operating system allows an appropriate range of loads (bullet weight, velocity, and powders) to cycle the firearm. It also minimizes, or eliminates, excessive energy transferred into the operating system thereby reducing wear on the firearm and perceived recoil to the operator. The amount of gas required to operate the operating system of a firearm can vary based on a number of factors. Installing a suppressor on a firearm generally increases the amount of gas sent through the operating system of a firearm so a previously optimally tuned firearm 10 is likely to be "over-gassed." Shooting slower ammunition (e.g. subsonic) ammunition can send less gas through the operating system so a previously optimally tuned firearm is likely to be "under-gassed."

20 Some user-adjustable piston operating systems comprise an indexed multi-position mechanism. These allow the user to adjust the amount of gas directed into the operating system and permit it to operate successfully with a wider range of ammunition. Many user-adjustable operating systems can become difficult, or impossible, to adjust if they 25 become excessively fouled. Fouling can occur when carbon or other materials in the gas are deposited in the operating system.

DESCRIPTION OF RELATED ART INCLUDING INFORMATION DISCLOSED UNDER 37 CFR 1.97 AND 37 CFR 1.98

Not Applicable

BRIEF SUMMARY OF THE INVENTION

An indexed adjustable gas block system which is adjustable using a lever which may be installed in various positions according to the need of the user and which minimizes 40 fouling of the indexing portion of the operating system.

BRIEF DESCRIPTION OF THE SEVERAL VIEWS OF THE DRAWING

45 FIG. 1 is an exploded view of the applicant's invention from the top breech perspective.

FIG. 2 is a perspective view of the applicants from the lower-muzzle end.

50 FIG. 3 is a perspective view of the applicant's invention from the top.

FIG. 4 is an exploded perspective view of the applicant's invention from the bottom.

FIG. 5 is an exploded perspective view of the applicant's invention from the lower muzzle end.

55 FIG. 6 is a horizontal section view of the applicant's invention from the side.

DETAILED DESCRIPTION OF THE INVENTION

60 The applicant's invention is an indexed adjustable gas block for a firearm. The gas block may be used in piston or direct impingement firearms. The gas block is comprised of three primary elements: a body 101, a handle 111, and an adjustment screw 110. The body 101 is configured with a barrel hole 102 configured to accept passage of a firearm barrel. The body 101 contains features to allow the body 101

to be secured to a firearm barrel. In a preferred embodiment, those features are one or more threaded barrel attachment holes **103** passing through the body perpendicular to the barrel hole. The body is configured with a slot **104** separating a biasing portion **105** of the body **101** from a gas portion **115** of the body **101**. The biasing portion **105** of the body **101** is configured with an adjustment screw passage hole **106** configured to permit an adjustment screw **110** to pass through the biasing portion **105** of the body **101**. In a preferred embodiment, the adjustment screw passage hole **106** is smooth rather than threaded. The gas portion **115** of the body **101** is configured with a gas tube hole **116** (exit gas port) parallel to the barrel hole. The gas tube hole **116** is connected to the barrel hole **102** by an obstruction cavity **601** (an opening configured to accept the tip **107** of the adjustment screw **110**) which is connected to the a gas port **401** (entry gas port). Gas may travel from the entry gas port **401**, through the obstruction cavity **601**, and then through the gas tube hole **116**. The gas portion **115** of the body **101** may be further configured with a gas tube pin hole **114** perpendicular to the gas tube hole **116**. The gas tube pin hole **114** is positioned such that when a gas tube roll pin is inserted into the gas tube roll pin hole **114**, the roll pin partially encroaches into the gas tube hole **116**. In an alternative embodiment, the exit gas tube port is configured to operate on a piston system rather than a direct impingement system.

The biasing portion **105** of the body **101** is configured with a detent installation hole **502** which connects the barrel hole **102** to the adjustment screw passage hole **106**. The biasing portion **105** of the body **101** is further configured with a detent hole **503**. The detent hole **503** is configured to accept a biasing member and an interfacing member. In a preferred embodiment, the biasing member is a spring and the interfacing member is a ball bearing where the spring is installed between the ball bearing and end of the detent hole **503** farthest from the barrel hole.

A handle **111** is configured to attach to the adjustment screw **110**. The handle **111** has a thickness less than the width of the gap **104** separating the gas portion **115** of the body **101** from the detent portion **105** of the body **101**. The handle **111** is configured with an adjustment screw passage hole **113** passing through the thickness of the handle **111**. The handle **111** is also configured with an adjustment screw attachment hole **112** passing through the length of the handle terminating in the adjustment screw passage hole **113**. In a preferred embodiment, the adjustment screw attachment hole **112** is threaded. The handle **111** may be attached to the adjustment screw **110** by tightening a screw into the adjustment screw attachment hole **112**. In a preferred embodiment, a first headless screw is tightened into the adjustment screw attachment hole **112** and a second headless screw is tightened into the adjustment screw attachment hole **112** against the first headless screw as a jam screw to prevent both headless screws from accidentally loosening.

The adjustment screw **110** is comprised of a threaded portion **108**, an indexing portion **109**, and a tip **107**. The threaded portion is threaded to cooperatively interface with threads contained in the adjustment screw adjustment hole **501**. Adjustment screw adjustment hole **501** terminates in the obstruction cavity **601** in the gas portion **115** of the body **101** on the side of gas port **401** opposite the detent portion **105** of the body **101**. In a preferred embodiment, the diameter of the shaft of the tip **107** portion of the adjustment screw **110** is approximately equal to the width of the obstruction cavity **601** of the gas block such that when the tip **107** portion of the adjustment screw **110** passes through the obstruction cavity **601** of the gas block **101** to its

maximum extent, gas is substantially prevented from passing through the obstruction cavity **601** of the gas block **101** into the gas tube hole **116**. The adjustment screw **110** is further comprised of an indexing portion **109**. In a preferred embodiment, the indexing portion **109** of the adjustment screw **110** is comprised of a series of lengthwise grooves. In an alternative embodiment, the indexing portion **109** is comprised of a series of flat regions. The shape of the indexing portion **109** is selected to cooperatively interface with the end of a headless screw used to attach the handle **111** to the adjustment screw **110**. The shape of the indexing portion **109** is also selected to cooperatively interface with an interfacing member (detent) installed in the biasing portion **105** of the body **101**. The thread pitch of the threaded portion **108** of the adjustment screw **110** is selected in conjunction with the spacing of the lengthwise grooves in the indexed portion **109** such that a desirable amount of insertion or removal of the tip portion **107** of the adjustment screw **110** from the obstruction cavity **601** is achieved as sequential features in the indexed portion **109** of the adjustment screw **110** face the detent hole **503**. In a preferred embodiment, the end of the adjustment screw **110** opposite the tip **107** portion is configured with a features, such as a hexagonal depression or slot, to facilitate insertion of a tool to aid in rotating the adjustment screw **110**.

The invention is used by inserting a biasing member and an interfacing member (detent) into the detent hole **503**. The interfacing member is held in place, with a tool if necessary through the detent installation hole **502**, while the adjustment screw **110** is inserted through the adjustment screw passage hole **106** thereby capturing the interfacing member and biasing member. The adjustment screw **110** is then further pushed through the adjustment screw passage hole **113** and into the adjustment screw adjustment hole **501** until the threads of the adjustment screw **110** meet the threads of the adjustment screw adjustment hole **501**. The adjustment screw **110** is then screwed into the adjustment screw adjustment hole **501** to the desired depth which results in the desired amount of opening in the obstruction cavity **601**.

The handle **111** is then attached to the adjustment screw **110**. This is preferably achieved by screwing a first headless screw into the adjustment screw attachment hole **112** until the end of the screw closest the adjustment screw fits against or in a feature in the indexing portion **109** of the adjustment screw **110**. A second headless screw is then screwed into the adjustment screw attachment hole **112** until the second headless screw contacts the first headless screw such that the second headless screw acts as a jam screw. A user may then rotate the handle **111**, thereby rotating the adjustment screw **110**, to increase or decrease the amount of the obstruction cavity **601** obstructed by the tip **107** portion of the adjustment screw **110**. Increasing the amount of the obstruction cavity **601** obstructed by the tip **107** portion of the adjustment screw **110** will decrease the amount of gas permitted to pass from the entry gas port **401** into the gas tube hole **116**. Decreasing the amount of the obstruction cavity **601** obstructed by the tip **107** portion of the adjustment screw **110** will increase the amount of gas permitted to pass from the barrel through the entry gas port **401** into the gas tube hole **116**.

A gas tube is then inserted into the gas tube hole **116** to the desired depth. A roll pin is then driven into the gas tube pin hole **114** thereby capturing the gas tube. The body **101** is then installed on a barrel with the barrel passing through the barrel hole **102**. The body **101** is then secured on the barrel. In a preferred embodiment, the body is secured on the barrel by one or more screws threaded into one or more

5

barrel attachment holes 103 where the ends of the screw(s) contact the barrel. Other means of attaching the gas block, including clamp-type and two-piece gas blocks are well known in the art and may be used without deviating from the present invention.

The invention claimed is:

1. An adjustable gas block system for a semi-automatic firearm comprising:

a) a gas block configured to be attached to a firearm barrel having a gas port comprising:

- 1) an entry gas port configured to allow gas to enter the gas block from the firearm barrel gas port,
- 2) an exit gas port configured to allow gas to exit the gas block,

3) an obstruction cavity disposed between the entry gas port and the exit gas port fluidly connected to both the entry gas port and the exit gas port;

b) an adjustment screw comprising:

- 1) threads configured to cooperatively interact with threads in the gas block,
- 2) a gas restricting portion wherein movement of the adjustment screw within the gas block alters the volume of obstruction cavity open to the passage of gas from the entry port to the exit port, and

3) an indexing portion; and

c) an adjustment handle, having a physically-limited range of motion, configured to be attached to the adjustment screw in a plurality of orientations wherein:

1) the physically-limited range of motion of the adjustment handle at a first extreme prevents movement beyond that which causes the gas restricting portion of the adjustment screw to occupy a user-configurable minimal volume of the obstruction cavity of the gas block,

2) the physically-limited range of motion of the adjustment handle at a second extreme prevents movement beyond that which causes the gas restricting portion of the adjustment screw to occupy a user-configurable maximal volume of the obstruction cavity of the gas block, and

3) the orientation of the adjustment handle relative to the adjustment screw is user-configurable and selected to cause the desired volume of obstruction cavity open to the passage of gas be achieved at an extreme of the physically-limited range of motion of the adjustment handle.

2. The adjustable gas block system of claim 1 further comprising a biasing system.

3. The adjustable gas block system of claim 2 wherein the gas block further comprises a slot approximately orthogonal to the firearm barrel and through which the adjustment screw passes.

4. The adjustable gas block system of claim 3 wherein the slot in the gas block is disposed between the biasing system and the obstruction cavity.

5. The adjustable gas block system of claim 2 wherein the biasing system comprises:

6

a) a biasing member configured to interface with the indexing portion of the adjustment screw and resist rotation of the adjustment screw; and

b) a pressure applying means configured to apply pressure on the biasing member.

6. The adjustable gas block system of claim 5 wherein the pressure applying means comprises:

a) a cavity in the gas block beginning at a location selected to correspond with the indexing portion of the adjustment screw and ending in the gas block; and

b) a spring which applies pressure on the end of the cavity ending in the gas block and the biasing member.

7. The adjustable gas block system of claim 4 wherein the adjustment handle attaches to the adjustment screw in the portion of the adjustment screw passing through the slot in the gas block.

8. The adjustable gas block system of claim 4 wherein the adjustment handle extends beyond an outer perimeter of the gas block when the adjustment handle is installed on the adjustment screw.

9. The adjustable gas block system of claim 4 wherein the adjustment handle does not extend beyond an outer perimeter of the gas block when the adjustment handle is installed on the adjustment screw.

10. The adjustable gas block system of claim 4 wherein the adjustment handle attaches to the indexing portion of the adjustment screw by means of a threaded member passing down a tapped hole traversing at least a portion of the length of the adjustment handle to interface with the indexing portion of the adjustment screw.

11. The adjustable gas block system of claim 10 wherein the threaded member attaching the adjustment handle to the adjustment screw is secured by a jam screw.

12. The adjustable gas block system of claim 1 wherein the indexing portion of the adjustment screw comprises a plurality of longitudinal grooves.

13. The adjustable gas block system of claim 1 wherein the indexing portion of the adjustment screw has a polygonal cross-section.

14. The adjustable gas block system of claim 1 wherein the threaded portion of the adjustment screw comprises multiple start threads.

15. A method of tuning the adjustable gas block system of claim 1 comprising:

a) installing the adjustment screw into the gas block until the gas restricting portion of the adjustment screw leaves open the desired volume of obstruction cavity open to the passage of gas from the entry port to the exit port; and

b) attaching the adjustment handle to the adjustment screw at a desired orientation.
